UNITED STATES PATENT OFFICE

WALTER D. TEAGUE, OF FOREST HILLS, NEW YORK, ASSIGNOR TO GENERAL REGISTER CORPORATION, OF BROOKLYN, NEW YORK, A CORPORATION OF PENNSYLVANIA

DESIGN FOR A TICKET ISSUING MACHINE CABINET

Application filed February 27, 1932. Serial No. 43,022. Term of patent 7 years.

To all whom it may concern:

Be it known that I, WALTER D. TEAGUE, a citizen of the United States, residing at Forest Hills, county of Queens, and State of New York, United States of America, have invented a new, original, and ornamental Design for a Ticket Issuing Machine Cabinet, of which the following is a specification, reference being had to the accompanying drawing, forming part hereof.

The drawing shows a perspective view of the ticket issuing machine cabinet, showing my new design.

I claim:

The ornamental design for a ticket issuing machine cabinet, as shown.

WALTER D. TEAGUE.
